UNITED STATES PATENT OFFICE.

WILLIAM STUEBING, SR., OF CINCINNATI, OHIO.

DEVICE FOR PUNCHING AND CUTTING EYELETS.

Application filed February 21, 1924. Serial No. 694,816.

The object of my invention is to produce, as a single unit, a removable device for punching and cutting eyelets or hangers used for calendars, signs, advertising matter to be suspended, and for like purposes.

Usually the punching and eyelet or hanger cutting mechanism is built into and is part of the machine, see the patent of William Stuebing, Sr., machine for mounting metal strips, No. 1,057,295, of March 25th, 1913.

Machines of this class are quite complicated and readily get out of order when the eyelet or hanger punching and cutting means get out of order, parts must be sent to the manufacturer and the machine will be idle until new parts are furnished, or a high class expert mechanic must be employed to correct the fault or defect, and the machine being idle, time and money are lost.

I overcome these objections by forming the unit punch and cutter as shown in the drawings. Two or three can be kept on hand by the user, and when one gets out of order a new one can be slipped in place by almost anyone, consequently the machine is stopped momentarily, and the device, which is out of order, can be returned to the factory and repaired.

The attachment or device is simple, cheap, and highly efficient, and can be readily placed in position or moved.

In the accompanying drawing forming part of this specification:

Fig. 1, is a side view of the punching and feeding mechanism, with part of the punch operating attachment shown, parts being in section,

Fig. 2, is a top view of the punch and cutting means,

Fig. 3, is a side elevation, partly in section of the complete punching and cutting unit or device taken on line 3-3 of Fig. 2,

Fig. 4, is an inverted view of punch and upper knife support, parts being in section, taken on line 4-4 of Fig. 3,

Fig. 5, is a top or plan view of the lower part of the punching and cutting device, showing the lower knife and punching die, and connecting parts, parts being in section, taken on line 5-5 of Fig. 3,

Fig. 6, is a view in elevation of the complete unit or device,

Fig. 7, is a plan view of the eyelet or hanger, the strip or tape partly trimmed and punched at one end, and

Fig. 8, is a plan view of a complete eyelet or hanger.

In carrying out my invention, I provide a body consisting of a cylindrical lower part 1, and a head 2, generally made integral, the head being circular and of greater diameter than part 1.

The body parts 1 and 2, are positioned and kept from moving by reason of screws 38, see Fig. 2.

Through the parts 1 and 2, I place holes 3, there being two of said holes; these holes receive the shafts 4, 4, spaced as shown and are united at bottom by a clevis bracket 5, the clevis bracket held on the shaft 4, 4, by reason of nuts 6, 6, which are screw-threaded on the lower ends of said shafts 4.

At the upper end of shafts 4, 4, I place the punch and upper knife support 7, which is held to shafts 4 by reason of nuts 8, 8, screw-threaded onto the upper ends of shafts 4, the rear end of this support being tapered off at point 9 for clearance.

Through the center of support 7, I place a slot 10, and in the rear end of this slot I place the cutting knife 12, which is held firmly to support 7 by reason of screw 13. This knife is adjustable forwardly and backwardly in said slot, so that it will line up with the lower knife.

At the front part of support 7, I place the punch 14, which is held to the support 7 by reason of a screw 15.

Surrounding the shafts 4, attached to head 2, I place a stripper plate 16, which is suitably cut out to allow the punch and knife to pass through without friction.

The stripper plate 16 is rigidly held to the head 2 by reason of screws 39, see Fig. 5.

In the top of head 2, running forward and backward, I place a slot 17 which at the rear inclines to the top surface of head 2, this incline 18 lifts the eyelet strips and guides it into the machine in the proper position. Just in front of the rise of the incline and at right angles to slot 17, I place a slot 19 which receives the lower knife 20, and this lower knife has a concave cutting edge which conforms with the convex edge of the upper cutting knife 12, but may be of any other desired shape.

This lower knife 20 is held rigidly in its slot by reason of screws 21. The upper side of the lower knife 20 is on the same level or place with the bottom of slots 17, thus

allowing the same place for the eyelet strips 22 to pass over.

Near the front and in the slot 17, I place the punch die 23, the top surface of which being on the same plane as the bottom of slot 17. This punch is held rigidly in the head 2 by reason of a "press fit".

A clearance hole 24 passing through part 1, is somewhat larger than the hole in the die 23, thus allowing the punchings to fall out.

At the lower end of clevis bracket 5, are two downwardly depending arms 25, and form a clevis which receives a link 26, the link being movably attached to the arms 25 by reason of a pin 27 passing therethrough. At the lower end of link 26, a lever 28 is movably attached by reason of pin 29, parts of lever 28 being shown broken away.

20 In Fig. 1, it is plainly seen how the body portion 1 and head portion 2 are inserted in a bar 30 on the machine (not shown) the eyelet strip 22 passes over and through the roll 31, and roll 32, the roll 32 is held down 25 on roll 31 by a spring pressure from above (not shown), the eyelet strip 22 passing between said rolls 31 and 32, which feed said strip at predetermined intervals, said tape or strip then passing through a guiding 30 shoe 33, and then passing into and through slot 17 to be acted upon by the punch and knives which have hole 34 and cut round edge 35, which completes an eyelet, shown in Fig. 8.

35 By this continual operation the action is thus: the eyelet strip 22 passing through slot 17 to the desired length for the eyelet, the lever 28 which is acted on by a cam (not shown), presses down the link 26 and this link, in turn, acting on the clevis 5, which is attached to shafts 4, 4, pulls down said shafts, thus pulling down punch and knife support 7, and thus operating said punch and knife upon the eyelet strip, cutting out 40 the eyelet or hanger as soon as the cam nose (not shown), releases. The parts just described move up into normal position and release the eyelet strip 22, so same may be again fed forward for another operation;

this upward movement is actuated by a 50 spring (not shown).

The steps of cutting or making an eyelet is best shown on Fig. 7. It will be seen that one end of this strip 22 has a concave end at 26, which has been cut at same time 55 hole 34 was punched, thus making the distance from edge 36 and the hole 34 always the same. As the eyelet strip 22 moves forward for the next operation, the knives 12 and 20 will cut this strip just in back of 60 the holes 34 on dotted line 37, see Fig. 7; it will be understood that this dotted line is not printed on the strip, but is used and shown to describe the operation.

In order to remove the unit or device it 65 is only necessary to take out the clevis pin 27, and screws 38 in head 2, and pull out the combined punching and cutting unit from bar 30.

That part of the eyelet or hanger which 70 is at the concave end 36 is generally folded with the material or paper which forms the top of the calendar, card, or the like.

In this specification I have described one specific form of carrying my invention into 75 effect, it being the preferred form, however, it will be readily seen and understood that I may deviate from and change the various parts to some extent, said changes and modifications still falling within the scope of the 80 specification and claim.

What I claim as new and my invention and desire to secure by Letters Patent is:

In a device of the character described, a 85 body part carrying a head, said head carrying a die and a lower cutting knife in combination with shafts passing through said head and body part and capable of upward and downward movement, the shafts at their top carrying a supporting plate, said plate 90 provided with an upper cutting knife and a punch, the whole combined as a unit, for attachment to or removal from a machine.

In testimony whereof, I affix my signature at Cincinnati, Ohio, this 18th day of February, 1924.

WM. STUEBING, Sr.
